UNITED STATES PATENT OFFICE.

HARRY E. KHOURY, OF NEW BEDFORD, MASSACHUSETTS.

WARP STOP MOTION.

Application filed July 6, 1926. Serial No. 120,738.

The present invention relates to warp stop motions for looms, and more particularly to that type of stop motion wherein the harness or shed forming heddles perform the 5 additional function of detector wires, which serve to stop the loom whenever one of the warp threads breaks or drops.

Stop motions of this type are broadly old, and are illustrated, for example, in my Patents Nos. 1,527,195 and 1,527,196, granted 10 February 24th, 1925.

An object of the present invention is to provide a stop motion of this type which is simple in construction, positive and accurate in operation, and which may be readily applied to the loom.

A further object of the invention is to provide a mechanism which may be conveniently applied to any loom, irrespective of 20 the number of harnesses.

These and other objects of the invention, which will become apparent as the description proceeds, are accomplished by a mechanism which comprises, broadly, the usual 25 heddle frames, each having therein a detector bar having a rocking movement, the heddles being formed to lock the bar against such movement whenever one of the warp threads breaks or slackens. Adjacent the 30 heddles and upon the loom frame is positioned a bracket having therein a lever provided with a plurality of members, each engageable by a detector bar and serving to rock such detector bar as its heddle frame 35 moves. The lever is yieldingly held against movement, but when engaged by a locked bar, is actuated, and through suitable connections serves to stop the loom. These 40 connections comprise a member normally positioned out of the path of a continuously moving element or dagger upon the loom lay, and which is actuated by a locked bar into the path of the dagger. Upon engagement of the dagger with such member, the 45 latter, through connections with the shipper lever, serves to stop the loom.

The foregoing and other features of the invention will become clearer as the description proceeds in connection with the accompanying 50 drawings, wherein are shown preferred embodiments of the invention.

In these drawings:

Figure 1 is a side elevational view of the mechanism, with portions of the loom frame indicated in dotted lines to illustrate the

relation between the parts of the stop mechanism and the loom.

Figure 2 is a fragmentary elevational view showing the relation between a heddle frame and the contact parts which are mounted 60 upon the loom.

Figure 3 is a top plan view of the contact parts of the loom with portions of the bracket shown in horizontal section.

Figure 4 is a vertical section on the line 65 4-4 of Figure 2, showing the stiffening means for the detector bar and heddle frame cross rod.

Figure 5 is a section on the line 5-5 of Figure 2, showing the means for limiting the 70 rocking movement of the detector bar.

Figure 6 is a fragmentary sectional view at the end of the detector bar, as illustrated in Figure 2.

Figure 7 is an enlarged detail view of the 75 supporting bracket and lever illustrated in Figure 1.

Figure 8 is a view showing the normal position of the detector bar in one of the 80 heddles.

Figure 9 is a view showing the relative position of the heddle and detector bar when one of the warp threads breaks and the heddle drops.

Figure 10 is a side elevational view of a 85 modified form.

Figure 11 is a rear elevational view of the form illustrated in Figure 10, looking from the rear of the bracket.

Figure 12 is a view showing the relation 90 of the heddle and detector bar before breakage of one of the warp threads.

Figure 13 is a view showing relation of the parts in Figure 12 when one of the warp 95 threads breaks, and

Figure 14 is a vertical section on the line 14-14 of Figure 10, looking in the direction of the arrows.

Referring to the form of the invention illustrated in Figures 1 to 9 inclusive, 10 indicates diagrammatically the side frame of a loom, having the usual upstanding arm 10' supporting, by the straps 11, the heddle frames 12.

The heddle frames, one of which is illustrated in Figure 2, are of usual rectangular formation, having upper cross pieces 13 connected by vertical side pieces 14. Upper and lower cross bars 15' connect the side pieces and provide a rigid rectangular struc- 110

ture. In each heddle frame there is mounted, preferably adjacent the upper cross rod 15, a detector bar 16, which is mounted to have a rocking detector movement. Each detector bar is angular in cross section, as illustrated in Figures 8 and 9, and extends through openings 17 in the heddles. The heddle openings 17 are formed to permit free rocking movement of the bars 16 when the warp threads are unbroken, but are adapted to lock the bar against such movement whenever one of the warp threads breaks. For this purpose, the slots 17, through which the cross rods 15 also extend, preferably below the detector bars, are reduced, as indicated at 17', to receive a rib 16' upon the detector bar (Figure 9). As will be understood, whenever one of the warp threads breaks, its heddle will drop, causing the rib 16' to fit within the reduced slot 17', whereupon the detector bar will be held against rocking movement, and through suitable mechanism, when the heddle frame descends, effect stoppage of the loom.

The mechanism thus far described is broadly old, but there are certain details of the related structure which are novel.

In the first place, it has been found desirable to limit accurately the rocking movement of the detector bar, preferably in either direction, and for this purpose, complementary means is provided upon the heddle frame and detector bar, such means taking the form of a collar 18 fixedly and adjustably secured to the detector bar, as by means of a set screw 19, cut away at 20, for a portion of its circumference (Figure 5) to receive a fixed stop 21 upon the heddle frame. The bar is normally maintained in one extreme position by means of a coil spring 22 surrounding its projecting end (Figure 6), one end of the spring being anchored at 23 to the heddle frame, and the other end 24 extending through and secured to a sleeve 25 fastened upon the end of the detector bar as by means of a set screw 26. It will be understood that the spring normally tends to rotate the bar to which it is connected, through the collar 25, in a counterclockwise direction, as viewed in Figure 1, and movement in this direction is limited by the stop 21. The bar is provided upon the sleeve 25 with an eccentric projecting pin 27, which serves to engage suitable means upon the loom as the heddle frame descends, and by such means, the bar has imparted thereto, a detecting movement in a clockwise direction, as viewed in Figure 1. Movement in this direction is limited also by the stop 21 engaging the opposite end of the circumferential slot 20 in the stop collar.

Another feature of the detector bar mounting and related parts consists in means for maintaining the bar rigid. This means pref-

erably consists of a bracket 28 secured to the heddle frame (Figure 2), and having positioned thereon for sliding movement, an angularly formed bracket portion 29, one wall 29' of which extends across the plane 70 of the detector bar and cross rod 15. This wall is provided with slots 30, 31 to receive the detector bar and cross rod, and by vertically adjusting the bracket 29, by means of the screw 32 fitting through a slot in the bracket portion and serving to clamp the same with the remainder of the bracket 28, the detector bar and rod may be snugly fitted within the slots 30, 31, and reinforced. An important feature of this reinforcing means is the adjustable bracket 29, which may be adjusted after the heddle frame is arranged in the loom and connected with the upper and lower harness straps. These straps and connected parts serve to tension the heddle frame, and after their connection with the latter, the upper cross rod 15 and detector bar may be suitably reinforced by the bracket 28 and its adjustable portion 29.

It will be understood that the portion of the strap mechanism thus far described is broadly old, with the exception of (1) the stop means for limiting rocking movement of the detector bar; (2) the construction of the spring means for maintaining the bar in a normal position; and (3) the reinforcing means for the bar.

Referring to the remainder of the structure, it will be understood that there is provided means adapted to impart to the detector bar a rocking detector movement. This means preferably takes the form of a bracket having a supporting plate 34 in which is positioned a bored boss 35, serving to receive a pin or stud 36, secured to the loom frame 10, the bracket plate being secured to the stud 36 by means of a set screw 37. A bracket arm 38 extends laterally from the plate 34 and is provided with an elongated slot 39 through which passes the stud 36 and also a bolt 40 secured to the plate 34 and carrying a clamping nut 41. The bolt and stud maintain the laterally extending arm horizontal, due to the fact that they are spaced apart, and by means of nut 40, the arm may be fixedly held in any selected position to which it may be longitudinally moved for a purpose which will be clear as the description proceeds. The outer end of the arm 38 has spaced vertical fingers 42, 43, forming a fork which serves to support a pivot stud 44 for a lever 45. This lever is mounted upon the pivot 44 as a horizontal axis, and extends inwardly from the loom frame to a position beneath the pins 27 upon the detector bars. It will be observed that the lever has separate portions 46, which, preferably, carry vertically adjustable T contact elements, each arranged directly in the path of an eccentric pin 27 120

upon a descending heddle frame. By longitudinal adjustment of the bracket portion 29, which may be effected simply by releasing the clamp nut 41, these contact elements 5 upon the lever may be arranged in proper position, and vertical adjustment of the latter will insure engagement with the detector bar projecting pins 27 at the proper point in the descent of the heddle frame. As will 10 be understood, such contact will effect rocking movement of the detector bar, and to prevent movement of the lever when this engagement occurs, yielding means, such as the spring 48 (Figure 2), may be connected 15 to the lever at the opposite side of its axis from the contacting members. It will be observed that the spring 48 is anchored at 49 to the bracket, and its opposite end is fastened to a screw 50 extending freely 20 through the lever 45, a stop nut 51 upon the lever serving as means for varying the tension of the spring 48. By adjustment of the nut 51, the position of the lever may be changed, and the advantage of this arrangement 25 will be clear from the following description of the connections of the lever with the remainder of the stop mechanism.

It will be understood that when the lever is depressed by a locked detector bar, the 30 loom will be stopped. The rear end of the lever (Figure 2) receives a link 52, which is fastened to the lever by means of a set screw 53. The link 52 is freely connected to a second link 52', which, in turn, is connected 35 to a member 54 pivotally mounted upon a lug 55 fastened to a reciprocable rod 56, slidable in a bearing bracket 57 on the loom frame. When the lever 45 is in its normal position illustrated in Figure 2, the member 54 will be positioned as illustrated 40 in Figure 1, in which it is arranged just out of the path of a continuously moving element 59, preferably arranged upon the lay L. When the lever is depressed by the detector bar, the end of the member 54 to 45 which the link 52 is connected, will be raised, thus depressing the other end into the path of the dagger 59. Upon the next movement of the lay toward the member 54, the dagger 59 will engage the end of the member 54, and such engagement will shift the member 54 longitudinally. This rod is connected to a knock-off member 60, which 50 engages the loom shipper lever S, and, as will be understood, effect stopping of the loom.

It is thought that the operation of the mechanism described will be entirely clear from the foregoing description. The construction which is one which may be readily applied to any loom, irrespective of the 60 number of heddle frames, it being simply necessary to position in the bracket arm 39, a lever 45 having a suitable number of contact elements for engagement with the eccentric arm upon the detector bar of each heddle frame. The ready adaptability of the mechanism is due also to the adjustable parts of the supporting bracket, the means for varying the tension of the spring 48, 70 which will alter the position of the lever 45 and of the member 54, which is engageable by the dagger 59. Furthermore, due to the fact that the contact elements in the lever 45 may be vertically adjusted, it is always 75 possible to obtain engagement of the detector bars with these contact elements at just the proper point in the travel of the heddle frames.

Referring to Figures 10 to 14 inclusive, 80 there is shown a modified construction, in which 61 indicates a portion of the usual harness frame having cross or guide rods 62 therein, which extend through openings 63 (Figure 12) at the upper and lower ends of 85 the heddles 64. Each heddle also has passing therethrough, a detector bar 65, supported in the harness frame. The detector bar is mounted for free movement, preferably a rocking one, about its longitudinal axis, and, 90 as will be noted from Figure 12, extends freely through the heddles, which, when in normal position, permit a rocking movement of the detector bar. Each heddle is, however, formed from a narrowed portion 66, 95 and when one of the warp threads breaks, the heddle will drop, as illustrated in Figure 13, with the result that the detector bar, which is of angular formation, enters the narrowed portion, and is thereby locked by 100 the falling heddle against movement.

The detector bar is yieldingly held against movement by means of a coiled spring 67, having one end anchored in the heddle frame, and the other end extending into a collar 68 upon the bar, the collar being fixed in position by means of a set screw 69. To limit the movement of the detector bar under the influence of this spring, the bar has positioned therein, within the frame, a collar 70, 105 provided with a stop lug 71, which engages a complementary stop lug 72 on a collar 73, this collar being arranged adjacent the bar, preferably on the fixed guide rod 62. As illustrated clearly in Figures 10 and 14, the 110 two lugs will prevent the spring from moving the bar from the normal position illustrated in Figures 10 and 12.

It will be understood that as the heddle frame descends, the detector bar is given a 115 rocking movement in one direction by mechanism which will be later described, and when the frame is raised, the rod is returned in the opposite direction, by means of the spring, movement under the influence of the spring being limited by means of the stop lugs.

As in the form previously described, so long as the detector bar is free to rock under the influence of the mechanism to be de- 120 125 130

scribed, the stop mechanism is inoperative, but should one of the warp threads break or sag, its heddle will drop to the position illustrated in Figure 13, and the detector bar entering the narrow slot 66 will be held or locked against rocking movement. When in this position, the detector bar serves to operate the mechanism, which constitutes the present invention, and thereby to stop the loom.

Referring now to the features of the present invention which constitute improvements over the construction disclosed in my patents before mentioned, F (Figure 10) indicates a fixed portion of the loom, such as the frame, upon which is mounted a bracket consisting of a back strip 74 having openings 75 therein, through which may be passed means for securing the bracket to the loom frame. The bracket has outstanding side plates 76, which serve to support a horizontal pivot or fulcrum shaft 77, upon which is mounted a series of levers extending horizontally, and at their ends adjacent the heddle frames provided with means adapted to engage the detector bar and rock the same as the harnesses fall. This means, in the present instance, is in the form of upstanding forked members 78', each having a shank 79 entering the lever and adjustably secured by means of a set screw 80. As will be understood, there is provided a single lever 78 and its forked member 78' for each detector bar, and the latter carries on the collar 73, an eccentric arm or pin 81, which projects between the fingers of the forked member 78', and as the harness frame is lowered, engages an abutment in the form of a roller 82 in the fork, this engagement causing the detector bar to be rocked in a counterclockwise direction, as viewed in Figure 11.

Each lever 78 has associated therewith, means for yieldingly retaining it against movement, and in a fixed normal position, unless its associated detector bar is locked. This means may be in the form of an outwardly extending spring arm 83 beneath each lever, and engaging it at one side of the axis or fulcrum adjacent the portion which carries the member 78'. The upward movement of the lever, under the influence of the spring arm 83 may be limited by means of a stop or detent 84, pivotally mounted upon a shaft 85 extending between the side plates 76. The lower end of the detent normally engages a shoulder 86, and thus limits upward movement of the lever. The same detent serves also as means for retaining the lever in depressed position when it is lowered by the engagement therewith of a locked detector bar. It will be noted that each stop has an upwardly projecting portion which affords sufficient weight to cause the stop to gravitate downwardly in a clockwise direction when the lever is depressed,

and thus engage a second shoulder 87 (Figure 10), and in this position of engagement with the lever, it retains the latter in depressed position.

As will be observed, the bracket, with the series of levers 78 arranged side by side upon the pivot or fulcrum shaft 77, constitutes a compact mechanism which may be arranged adjacent the harnesses, each lever being provided with upstanding means at its free end to receive the eccentric arm 81 of a detector bar. Any number of levers may be arranged on the shaft 77 corresponding to the number of harnesses, and mechanism is provided so that when any one of the levers is depressed by a locked bar, the loom will be stopped, for instance, by operation of the shipper lever.

This mechanism, which will now be described, comprises a lever 88 pivoted at one end 89 on the outwardly projecting portion of the detent shaft 85, the lever being connected at its other end 90 to a pitman or link 91, which extends downwardly, and is pivotally connected to a forked rod 92 pivoted upon a stud 93 carried by a fixed bracket 94. The bracket 94 is fixedly secured to a longitudinally slideable bar 95 supported by suitable means (not shown) on the loom frame, and having a hooked end 96 which serves to engage the shipper lever S.

The rod 91 is arranged adjacent the path of a pin or dagger 97 upon the lay, a portion of which is indicated by the reference character L (Figure 11). When the rod 91 is in the position shown in Figure 11, the operation of the lay will not cause engagement of the pin 97 with the fork 92; however, as will be understood, it is intended that depression of any one of the levers 78 by means of a locked detector bar, will raise the rod 91 into the path of the dagger 97 on the lay, and engagement of the dagger with the fork will shift the bar 95 longitudinally and thereby operate the shipper lever. The fork 92 may be swung upwardly by any one of the levers 78, through the lever 88 and link 91, and for this purpose, the lever 88 carries a rod 99 which extends over the rear ends of the levers 78, and will be engaged by any lever when the same is depressed at its opposite end by a locked detector bar.

It will be observed that the mechanism is of very compact character, and may be readily applied to a loom and accommodated to a loom having any number of harnesses, simply by mounting the bracket carrying the levers 78 upon the loom frame adjacent the harnesses.

It is thought that the operation of the mechanism will be entirely clear from the foregoing description, it being understood that the levers 78 are normally in the position illustrated in Figure 10, and that their ends carrying the upwardly extending fork mem-

bers 78' will be depressed by a detector bar only when the same is locked, and in such instance, the depression of the levers will, through the lever 88 and link 91, raise the 5 rod 92 (Figure 11) into the path of the dagger 99, engagement between these two elements causing operation of the shipper lever S.

Obviously, the invention is not limited to 10 the specific embodiments illustrated and described, and such modifications come within its scope as are fairly within the terms of the following claims.

I claim:

15. 1. In a warp stop motion for looms, the combination with a heddle frame having a series of heddles supported by warp threads, a rockable bar mounted in the heddle frame, the heddles being formed to engage and lock 20 the bar against movement when one of the warp threads breaks, of means on the loom adapted to rock the bar as the heddle frame moves, said means comprising a bracket, a member pivotally mounted about a horizontal axis on said bracket but yieldingly held 25 against movement, said member being movable by the bar when locked as the heddle frame moves, a continuously moving element on the loom lay, and means having a link 30 connection with said member and the loom shipper lever and adapted to be moved into the path of said continuously moving element only when said bar is locked and moves said member.
35. 2. In a warp stop motion for looms, the combination with a heddle frame having a series of heddles supported by warp threads, a rockable bar mounted in the heddle frame, the heddles being formed to engage and lock 40 the bar against movement when one of the warp threads breaks, of means on the loom frame separate from the bar adapted to rock the bar as the heddle frame moves, said means comprising a bracket, a member pivotally mounted about a horizontal axis on said bracket but yieldingly held against movement, said member being movable by the bar when locked as the heddle frame moves, a continuously moving element on the loom 45 lay, and means operatively associated with said member and the loom shipper lever and adapted to be actuated by said continuously moving element only when said bar is locked and moves said member.
50. 3. In a warp stop motion for looms the combination with a heddle frame having a series of heddles supported by warp threads, of a rockable bar mounted in the heddle frame, the heddles being formed to engage and lock the bar against movement when one of the warp threads breaks, means on the loom adapted to rock the bar as the heddle frame moves, said means comprising a bracket, a lever mounted in said bracket, and 55 adapted to be actuated by the bar when the latter is locked, a continuously moving element on the loom, a member normally positioned out of the path of said element and operatively associated with said lever and the loom shipper lever, and yielding means for maintaining said lever in a normal position but adjustable to vary the position of the lever and said member, said lever when actuated by said bar serving to move said member into the path of said continuously moving element.
60. 4. In a warp stop motion for looms, the combination with a heddle frame having a series of heddles supported by warp threads, of a rockable bar mounted in the heddle frame, the heddles being formed to engage and lock the bar against movement when one of the warp threads breaks, means on the loom adapted to rock the bar as the heddle frame moves, said means comprising a bracket, a horizontally extending lever mounted in said bracket and adapted to be actuated by the bar when the latter is locked, a continuously moving element on the loom, a member normally positioned out of the path of said element and operatively associated with said lever and the loom shipper lever, and yielding means for maintaining said lever in a normal position but adjustable to vary the position of the lever and said member, said lever when actuated by said bar serving to move said member into the path of said continuously moving element.
65. 5. In a warp stop motion for looms, the combination with a heddle frame having a series of heddles supported by warp threads, of a rockable bar mounted in the heddle frame, the heddles being formed to engage and lock the bar against movement when one of the warp threads breaks, means on the loom adapted to rock the bar as the heddle frame moves, said means comprising a bracket, a horizontally extending lever mounted in said bracket, and adapted to be actuated by the bar when the latter is locked, a continuously moving element on the loom lay, a member normally positioned out of the path of said element and operatively associated with said lever and the loom shipper lever, and yielding means for maintaining said lever in a normal position but adjustable to vary the position of the lever and said member, said lever when actuated by said bar serving to move said member into the path of said continuously moving element.
70. 6. In a warp stop motion for looms, the combination with a plurality of heddle frames, each having a series of heddles supported by warp threads, and a rockable bar mounted in each heddle frame, the heddles being formed to lock the bar against rocking movement when one of the warp threads breaks, of means on the loom frame separate 75

- from the bars adapted to rock the bars as the heddle frames move and to be actuated by a locked bar in any one of the heddle frames to stop the loom, said means comprising a bracket, a lever mounted in said bracket and having a plurality of members each operable by a bar in one of said heddle frames, and means connecting said lever with the loom shipper lever adapted to stop the loom when the lever is actuated by a locked bar in any one of the heddle frames.
7. In a warp stop motion for looms, the combination with a plurality of heddle frames, each having a series of heddles supported by warp threads, and a rockable bar mounted in each heddle frame, the heddles being formed to lock the bar against rocking movement when one of the warp threads breaks, of means on the loom frame separate from the bars adapted to rock the bars as the heddle frames move and to be actuated by a locked bar in any one of the heddle frames to stop the loom, said means comprising a bracket, a lever mounted in said bracket and having a plurality of vertically adjustable members each operable by a bar in one of said heddle frames, and means connecting said lever with the loom shipper lever adapted to stop the loom when the lever is actuated by a locked bar in any one of the heddle frames.
8. In a warp stop motion for looms, the combination with a plurality of heddle frames, each having a series of heddles supported by warp threads and a rockable bar mounted in the heddle frame, the heddles being formed to lock the bar against rocking movement when one of the warp threads breaks, of means on the loom frame separate from the bars adapted to rock the bars as the heddle frames move and to be actuated by a locked bar in any one of the heddle frames to stop the loom, said means comprising a bracket, a lever mounted in said bracket having a plurality of members each engageable by a bar in one of said heddle frames, a continuously moving element on the loom, and a member operatively associated with said lever and the loom shipper lever and arranged to be engaged by said element only when the lever is actuated by a locked bar.
9. In a warp stop motion for looms, the combination with a plurality of heddle frames, each having a series of heddles supported by warp threads, and a rockable bar mounted in the heddle frame, the heddles being formed to lock the bar against rocking movement when one of the warp threads breaks, of means on the loom frame separate from the bars adapted to rock the bars as the heddle frames move and to be actuated by a locked bar in any one of the heddle frames to stop the loom, said means comprising a bracket, a lever mounted in said bracket having a plurality of members each engageable by a bar in one of said heddle frames, a continuously moving element on the loom, a member operatively associated with said lever and the loom shipper lever and arranged to be engaged by said element only when the lever is actuated by a locked bar, and yielding means connected with said lever and serving to hold the lever against movement except when engaged by a locked bar.
10. In a warp stop motion for looms, the combination with a plurality of heddle frames, each having a series of heddles supported by warp threads, and a rockable bar mounted in the heddle frame, the heddles being formed to lock the bar against rocking movement when one of the warp threads breaks, of means on the loom frame separate from the bars adapted to rock the bars as the heddle frames move and to be actuated by a locked bar in any one of the heddle frames to stop the loom, said means comprising a bracket, a lever mounted in said bracket having a plurality of members each engageable by a bar in one of said heddle frames, a continuously moving element on the loom, a member operatively associated with said lever and the loom shipper lever and arranged to be engaged by said element only when the lever is actuated by a locked bar.
11. In a warp stop motion for looms, the combination with a plurality of heddle frames, each having a series of heddles supported by warp threads, and a rockable bar mounted in the heddle frame extending through each heddle, the heddles being formed to lock the bar against rocking movement when one of the warp threads breaks, of means on the loom frame separate from the bars adapted to rock the bars as the heddle frames move and to be actuated by a locked bar in any one of the heddle frames to stop the loom, said means comprising a bracket, a lever mounted in said bracket having a plurality of members each engageable by a bar in one of said heddle frames, a continuously moving element on the loom, a member operatively associated with said lever and the loom shipper lever and arranged to be engaged by said element only when the lever is actuated by a locked bar, and yielding means connected with said lever and serving to hold the lever against movement except when engaged by a locked bar.
12. In a warp stop motion for looms, the combination with a plurality of heddle frames each having a series of heddles supported by warp threads, and a rockable bar mounted in the heddle frame extending through each heddle, the heddles being formed to lock the bar against rocking movement when one of the warp threads breaks, of means on the loom frame separate from the bars adapted to rock the bars as the heddle frames move and to be actuated by a locked bar in any one of the heddle frames to stop the loom, said means comprising a bracket, a lever mounted in said bracket having a plurality of members each engageable by a bar in one of said heddle frames, a continuously moving element on the loom, a member operatively associated with said lever and the loom shipper lever and arranged to be engaged by said element only when the lever is actuated by a locked bar.

by a locked bar in any one of the heddle frames to stop the loom, said means comprising a bracket, a lever mounted in said bracket having a plurality of members each engageable by a bar in one of said heddle frames, a continuously moving element on the loom, a member operatively associated with said lever and the loom shipper lever and arranged to be engaged by said element only when the lever is actuated by a locked

bar, and yielding means connected with said lever and serving to hold the lever against movement except when engaged by a locked bar, said yielding means being adjustable to change the position of said lever and the 15 said member engageable by the continuously moving element.

In testimony whereof I have hereunto set my hand.

HARRY E. KHOURY.
